UNITED STATES PATENT OFFICE.

JAMES PHILIP ERIE, OF NEW YORK, N. Y., ASSIGNOR TO THE ERIE EXPLO-
RATION COMPANY, OF SAME PLACE AND DOVER, DELAWARE.

CURRENT-REGULATOR.

SPECIFICATION forming part of Letters Patent No. 673,391, dated May 7, 1901.

Application filed January 4, 1901. Serial No. 42,099. (No model.)

To all whom it may concern:

Be it known that I, JAMES PHILIP ERIE, a citizen of the United States, residing in the city, county, and State of New York, have invented certain new and useful Improvements 5 in Current-Regulators, of which the following is a specification.

My invention relates to current-regulators, and has for its object to improve and simplify 10 such devices and adapt them for the purposes more particularly set forth hereinafter; and to these ends my invention consists in the various features of construction and arrangement of parts adapted to operate substantially as hereinafter more particularly set 15 forth.

Referring to the accompanying drawings, Figure 1 is a face view of the device, the rotating disk or brush - carrier being partly 20 broken away to show the segment - plates. Fig. 2 is a rear elevation with the operating handle removed to better show the parts and showing the rheostat and connections more in detail, and Fig. 3 is a vertical transverse 25 section through the medium plane of the device.

While my present invention is adapted for use in many and various relations wherein it is desired to control or regulate an electric 30 current and while the details of construction of the device may be varied from those shown and described in order to adapt it for various uses, it is intended more particularly for use in connection with a current-regulator of the 35 general type more fully set forth and described in my application, Serial No. 30,346, filed September 17, 1900; and the particular object of my present invention is to provide improved means for cutting off or controlling 40 the current supplied to the translating device, so that the current is allowed to flow to the translating device during short intervals, which intervals follow each other in rapid succession, and which intervals may be longer or 45 shorter, as required to produce the desired effect.

A further object of my present invention is to avoid the injurious effects caused by the spark produced in breaking the circuit.

50 The construction shown and presently to be described can be used in connection with the

circuits arranged substantially as shown in my prior application above referred to, and I do not deem it necessary herein to illustrate and describe such circuits in detail, and of course the device may be used in connection with other arrangements of circuits and, in fact, in any circuit where it is desired to accomplish the results intended. Among other uses to which it may be applied is in connection with the conversion of alternating 55 into direct currents, which direct currents are controlled or delivered to the translating devices at intervals of greater or less length or continuously, as may be desired. 60

With this general statement of the objects of my invention I will now proceed to describe more in detail the present embodiment thereof illustrated in the accompanying drawings. 70

Mounted on a suitable base A, which is preferably of insulating material, is a standard or support B, in which is fixedly supported a shaft or rod C. The upper portion B' of the standard is of suitable shape, preferably being extended, as shown, and is provided with a series of openings b, arranged around the shaft C, the purpose of which will hereinafter be explained. Mounted to rotate on the shaft C is a disk or plate D, the body 80 of which is preferably of insulating material, and arranged around the periphery thereof are a series of segments E E' E'', &c., which are insulated from each other, and which in the present instance are shown as having two 85 bearing or contact faces, one of which, e, is in the form of a groove in the periphery of the segments, and the other of which, e', is on the extended face of the segments. 75

Some means must be provided for making 90 electric contact with a segment or a number of segments on the disk D, and in the present instance I show a flexible contact device in the form of a band F, one end of which is secured to one of the segments in any suitable way, 95 as to the segment E, by means of a screw e'', while the other end of the band is secured to some suitable take-up device—as, for instance, a drum G, which is suitably mounted on a shaft G' in the extension B'' of the standard and is connected to some means for keeping the drum under stress, shown in the pres- 100

ent instance in the form of a coiled spring H, one end of which is secured to the casing H' and the other to the shaft G', and tends to turn the drum G in a direction to take up or 5 coil the flexible contact F upon the drum. With this construction it will be observed that by rotating the disk D a greater or less number of segments E E' E² may be brought into contact with the flexible contact F, and 10 the number of segments so in contact and included in the circuit can be adjusted and regulated by adjusting the disk D.

While any suitable means may be used for 15 adjusting the disk or plate D so as to include more or less of the segments in contact with the flexible contact F, I have shown a plate or arm I, loosely mounted upon the shaft C and connected with the disk D in any suitable way, as by the pin i, and this arm is provided with an opening i', corresponding in 20 position with the annular ring of openings b in the standard B. This arm I may be held in proper position on the shaft by any suitable means, as by a collar J, and further 25 mounted on the shaft C is an operating device or handle, shown in the form of a hand-wheel K, preferably of insulating material, having secured thereto a plate K', recessed to receive the collar J, and provided with a 30 pin k, adapted to engage the opening i' in the arm I, so that the hand-wheel and arm will move together, and thus move and adjust the disk D circumferentially on its axis.

In order to lock the parts in their adjusted 35 positions, the hand-wheel K is arranged to slide longitudinally on the shaft C, and the pin k is of such length that when in proper position it will engage the opening i' in the arm I; but when the hand-wheel is moved toward the standard B into the position shown in Fig. 3 the pin k also engages one or the other of the openings b in the standard, and it will thus be seen that the disk is securely 40 locked and held in its adjusted position. When it is desired to release the same, the hand-wheel K is moved outward on the shaft C until the pin k becomes disengaged from the opening b, and while still engaging the opening i' of the arm I the hand-wheel, arm, 45 and disk may be turned in either direction, as desired, to secure the proper adjustment of the segments and again locked in position. A thumb-nut K² or other suitable device is placed on the shaft C in such a position as to 50 permit the hand-wheel K to slide thereon the proper distance and prevent its disengagement from the arm I through the medium of the pin k.

In order to supply current to the segments, 55 various means may be used, which may be caused to pass over the face of the segments in succession; but in the present construction I have shown a disk or plate L, which is mounted on an insulating-hub L', secured to 60 a shaft L², which may be the armature-shaft of an electric motor or other device, by means of which the disk or plate may be caused to

rotate. Mounted on this disk is a brush or contact l, adapted to come in contact with the face of the segments, and the disk is also in 70 the present instance provided with a flange l', against the periphery of which a carbon brush or block l² bears, it being shown as mounted in a case l³ and supported by a spring l⁴ and connected by a plate l⁵ to a binding-post l⁶. Other means of supplying current to the disk may be used, but I find this 75 extremely satisfactory and effective. The other terminal of the circuit may be suitably connected with the segments, and I have shown 80 a binding-post l⁷ mounted on the base or standard B, and the connection is through the shaft G' to the drum G, and thence through the flexible contact F to the segments with which it is in contact. In the use of a device 85 of this character when the circuit is broken there is liable to be a spark, which is detrimental and destructive and otherwise objectionable, and in order to avoid these disadvantages I provide means for overcoming the 90 effect of the spark. In this instance the spark (if any) occurs as the brush l passes off the segment E onto the segment O, and I have divided the segment O into a number of small 95 segments circuit resistance devices, so that the circuit will not be completely broken at once, but a series of resistances will be introduced into the circuit before it is actually broken. Various connections may be made whereby 100 this is accomplished, and in the device shown I connect the segment E, for instance, to a ring R on the disk or plate D, and the portion o of segment O to a ring R', and the portions o' o² to the rings R² R³, respectively, 105 and I provide some means, as the spring-fingers r r' r² r³, which are suitably insulated from each other and from the standard and which bear upon the respective rings and 110 make connection with their respective segments whatever may be the position of the disk D.

The rheostat or resistance may be of any suitable construction; but as shown it comprises a box S, in which are mounted a number of insulating-strips s s' s² s³, &c., wound with wire of suitable resistance and connected to binding-posts on the box, and these posts are connected to the spring-fingers in the manner indicated. Thus the finger r, bearing on the ring R, connected to the segment E, is connected to the first binding-post, and the finger r', bearing on the ring R', connected to the segment o, is connected to the second binding-post, and the others are similarly 125 connected.

I find by experiment that it is best to introduce into the circuit a relatively small resistance and to gradually increase the same until the resistance is infinite or the break is 130 completed; and while I am not limited to any particular resistance in actual practice the insulating-strip s' is wound so that when the brush l passes from the segment E to the seg-

ment o a resistance of six ohms is introduced between the segments, and as the brush passes to segment o' a resistance of eighteen ohms is introduced, and as it passes to segment o^2 a resistance of sixty-five ohms is included between the adjacent segments. This arrangement of resistances is effective to choke or neutralize the current producing the spark, so that when the brush l passes onto the next segment, completely breaking the circuit, no appreciable spark will occur.

Such being the general construction of the device, its operation will be understood by those skilled in the art, and it will be seen that the disk D can be adjusted in any desired position, so that the flexible contact F will progressively include or exclude a greater or less number of segments E E' E^2 , &c., it being shown in the present instance in contact with the segments from E to E^8 and all of these segments from E to E^8 will be supplied with current, so that when the brush l in rotating comes in contact with the face of the segment E^8 the circuit will be completed and remain completed until the brush passes off the face of the segment E , and then when the resistance or rheostat device is used the circuit still remains completed through the rheostat until the brush l passes off the segment o^2 . The remaining segments being out of circuit, no current will pass during the movement of the brush l over such segments. In this way it will be seen that a very accurate and easily-adjusted device is provided whereby the intervals of the breaks may be nicely and satisfactorily regulated so as to include one or more of the segments, as desired.

It will be understood that when the disk is turned to cut out a number of segments the spring H will wind up the flexible contact F and keep it under tension and in contact with the peripheries of the desired number of segments.

Having thus described the preferred embodiment of my invention without limiting myself to the exact construction and arrangement described, what I claim is—

1. A current-regulator, comprising a movable series of segments, a flexible-band contact connected to one of the segments, and means for bringing the band into engagement with or disengaging it from the segments progressively, substantially as described.

2. A current-regulator, comprising a rotatable disk having a series of segments, a flexible contact connected to one of the segments, and means for holding the flexible contact under tension, whereby the flexible contact may positively engage more or less of the segments progressively, substantially as described.

3. In a current-regulator, the combination with a disk having a series of segments, of a flexible contact one end of which is connected to one of the segments, a drum under tension to which the other end of the contact is con-

nected, and means for adjusting the disk, substantially as described.

4. In a current-regulator, the combination with a rotatable disk carrying a number of segments, of a flexible contact connected to one of the segments, means for supporting the flexible contact under tension against the segments, and means for rotating the disk and securing it in position, substantially as described.

5. In a current-regulator, the combination with a rotatable disk carrying segments, of an arm connected to the disk and having an opening, and a handle provided with a pin engaging said opening, substantially as described.

6. In a current-regulator, a standard having openings, a shaft mounted in the standard, a disk mounted on the shaft, an arm also mounted on the shaft and connected to the disk and provided with an opening, and a handle provided with a pin to engage the opening in the arm and in the standard, substantially as described.

7. In a current-regulator, the combination with a disk provided with a series of segments, of a rotating disk provided with a brush and having a flange, and a contact-brush bearing on the flange, substantially as described.

8. In a current-regulator, the combination with a disk provided with a series of segments, of a rotating disk, a brush carried by the disk and bearing on the segments, and a spring-actuated contact-brush bearing on the periphery of said rotating disk, substantially as described.

9. In a current-regulator, a disk the body of which is of insulating material having a number of segments mounted thereon, the segments being provided with a peripheral groove and a flat face, substantially as described.

10. In a current-regulator, a disk the body of which is of insulating material having a series of segments mounted thereon, the segments having a peripheral groove, in combination with a flexible contact connected to one of the segments and adapted to bear in the groove, substantially as described.

11. In a current-regulator, the combination with a disk provided with a number of segments, of means for including a greater or less number of segments in the circuit, a circuit-breaking device, and means for avoiding sparking by progressively introducing resistance into the circuit prior to its ultimate break, substantially as described.

12. In a current-regulator, the combination with a series of segments more or less of which may be included in a circuit, of a circuit-breaker co-operating with the segments and means for avoiding sparking, comprising a series of insulated variable-resistance devices, whereby as the circuit is broken resistance will be progressively included in the circuit, substantially as described.

13. In a current-regulator, the combination with a disk carrying a number of segments, of means for including a greater or less number of segments in the circuit, a rotating brush for making and breaking the circuit, and a series of segments including resistance devices between the segments, whereby as the circuit is broken resistance will be progressively included in the circuit between the segments and sparking avoided, substantially as described.
14. A current-regulator, comprising a disk having a series of segments, means for including a greater or less number of segments

in the circuit, a series of insulated segments, 15 rings connected to said segments, spring-fingers bearing on the rings, a resistance device connected to the spring-fingers, and means for breaking the circuit and progressively including the resistance in the circuit before 20 final breaking, substantially as described.

In testimony whereof I have signed my name to this specification in the presence of two subscribing witnesses.

JAMES PHILIP ERIE.
